(57) **CLAIM**

The ornamental design for a shoe, as shown and described.

DESCRIPTION

1. Shoe

1.1 : Perspective

1.2 : Front

1.3 : Back

1.4 : Right

1.5 : Left

1.6 : Top

1.7 : Bottom

The shoe includes an upper and a sole; the upper features nearly radial ornamental stitching at the toe and wavy stitching on the sides; the sole has two longitudinal lateral bands with a toothed profile and a central band with a toothed profile offset from the profiles of the lateral bands, the three bands of the sole also extend, almost vertically, over the rear part of the upper.
